UNITED STATES PATENT OFFICE.

JOSEPH RABER, OF POPLAR BLUFF, MISSOURI, ASSIGNOR TO DALTON ADDING MACHINE COMPANY, OF ST. LOUIS, MISSOURI, A CORPORATION OF MISSOURI.

LINE-STOP AND SIGNAL DEVICE.

1,005,782.

Specification of Letters Patent. Patented Oct. 10, 1911.

Application filed January 18, 1909. Serial No. 472,827.

To all whom it may concern:

Be it known that I, JOSEPH RABER, a citizen of the United States, residing at Poplar Bluff, Missouri, have invented a new and useful Line-Stop and Signal Device, of which the following is a specification.

This invention relates to typewriting and recording machines, and particularly to line stop and signal devices of such machines, and it consists of the novel construction, combination and arrangement of parts herein shown, described and claimed.

In the accompanying drawings, Figure 1 is a perspective view of the complete invention. Fig. 2 is a rear elevation thereof. Fig. 3 is a sectional view of a support showing the arrangement of the stop signal operating device therein. Fig. 4 is a cross sectional view of said support on the line 20 4-4 of Fig. 2. Fig. 5 is a sectional view on the line 5-5 of Fig. 2.

1 indicates a stop bar which constitutes a part of the paper carriage and to which an adjustable stop 2 is attached, said stop being movable to vary it to any desired position thereon as required to permit the carriage to have greater or less movement as desired.

To the top 3 of the machine a bracket 4 is attached, to which is pivoted a member 5, said member being sustained in proper position by a spring 6 connecting same with the bracket 4. Two levers 7 are pivoted to the member 5 and at their upper ends are connected to a support 8 which is in the form of two plates having an integral connection as shown at 9. A spring 10 connects a downward extension 11 on the support 8 with the bracket 4, and holds said support 8 in a substantially horizontal position, the latter having a pin 12 engaging under an arm 13 on one of the levers 7, serving as a stop for the support 8. Near the inner end of the support 8 an operating pawl 14 is pivoted and is connected to the stop pawl 15 pivoted near the opposite end of said support by means of the spring 16, said spring acting to hold both the said parts in their idle positions. The pawl 14 is formed with an oblique inner surface so that as the paper carriage travels laterally the stop 2 will depress the inner end of the support 8 until said stop passes beyond the outer edge of said pawl 14, at which time the spring 10 will retract and

return the support 8 to its initial position. A spring arm 17 is attached to the support 8 and is provided with a weight 18 at its free end, which by the rapid operation of said support in returning to its idle position is thrown against the bell disk 19, sounding the same. After this audible signal the carriage may move a known distance until stopped by engagement of the stop 2 against the abutment bar 15 beyond which the carriage cannot move, except after removal of the member 15 from the path of the part 2. The arrangement is such that when the parts 2 and 15 are engaged, the levers 7 will be slightly oscillated by the pressure imparted to said part 15.

A bell crank 20 is pivoted at 21 to some stationary part of the machine and has a pin 22 on one arm extending into slots 23 in the lower ends of the levers 7, and has a link 24 connected to its opposite end whereby the key-locking mechanism is actuated and the keys rendered inoperative.

A link 25 is connected with the member 5 whereby said member and all the parts supported thereby may be turned downwardly. This is for the purpose of enabling the operator to remove the stop or abutment 15 from the path of the stop member 2 should it be desirable to record additional characters in the same line after engagement of the stop parts 2 and 15.

I am aware that there may be modifications and alterations in the construction and arrangement of the parts embodying this invention without departure from the spirit and scope of the invention, and I do not restrict myself to identical features of construction or arrangement, but

What I claim and desire to secure by Letters Patent is—

1. In a recording machine, line stop mechanism comprising a pivoted member, a spring holding said member in idle position, a support pivoted to said member, a spring holding said support in idle position, a stop movably carried by said support, a spring holding said stop in idle position, and a connection whereby said pivoted member and thereby said pivoted support and said stop may be moved to inoperative or ineffective position, substantially as specified.

2. In a recording machine, line lock and signal mechanism comprising a pivoted

member, a support carried by said pivoted member, means for moving said support, a signal, means for sounding said signal when said support is moved, and a carriage stop carried by said support, substantially as specified.

3. Line lock and signal mechanism comprising, in combination with the carriage stop member, a pivoted member, a support carried by said pivoted member, means for operating said support independently of said pivoted member when said stop member moves across said support, a signal, and means for sounding said signal when said support is moved, and a stop carried by said support, substantially as specified.

4. Line lock and signal mechanism comprising a support, signaling mechanism, means for causing said support to operate said signaling mechanism, and a carriage stop carried by said support limiting movement of said means, substantially as specified.

5. The combination with a pivoted stop support, of signaling mechanism, a device operable by said stop support to operate said signaling mechanism, a carriage stop pivoted on said support, and means for moving said carriage stop, substantially as specified.

6. In a recording machine, line stop mechanism comprising a pivoted member, a spring holding said member in idle position, a support pivoted to said member, a spring holding said support in idle position, and a stop movably carried by said support, substantially as specified.

7. In a recording machine, line stop mechanism comprising a pivoted member, a spring holding said member in idle position, a support pivoted to said member, a spring holding said support in idle position, a stop movably carried by said support, and a spring holding said stop in idle position, substantially as specified.

8. Line lock and signal mechanism for a carriage, supported independently of the carriage and comprising a pivoted support, signaling mechanism, means for causing said support to operate said signaling mechanism, and a carriage stop pivoted on said support, substantially as specified.

9. In a recording machine, a pivoted member, a spring holding said member in idle position, a support pivoted to said member, a spring holding said support in idle position, a stop movably carried by said support, a paper carriage stop arranged to operate said support during movement toward said first-named stop, and signal mechanism sounded by said support when said support is operated by said carriage stop, substantially as specified.

10. In a recording machine, line stop and signal mechanism comprising a pivoted member, a spring holding said member in

idle position, a support pivoted to said member, a stop abutment for said support, a spring holding said support, in idle position against said stop abutment, a movable stop, carried by said support, a bell disk, a weight carried by said support, a paper carriage stop arranged to move toward and engage with said movable stop, and means whereby said carriage stop will cause said weight to strike said bell disk at a predetermined time, substantially as specified.

11. Line lock and signal mechanism comprising a support, a spring holding said support in idle position, a stop pivoted on said support, a carriage stop movable toward said first-named stop, signal mechanism, and means for moving said support effectively to sound said signal mechanism when said carriage stop passes a given point in its movement toward said first-named stop, substantially as specified.

12. Line lock and signal mechanism comprising a pivoted support, a spring holding said support in idle position, a line stop carried by said support, a carriage stop movable toward said line stop, a bell disk, a weight or hammer carried by said support, and means on said support whereby said carriage stop will move said support effectively to cause said weight or hammer to strike said bell disk.

13. Line lock and signal mechanism comprising a pivoted support, a stop on said support, a carriage stop movable toward and whose movement is limited by said first-named stop, manipulative means for moving said first-named stop out of the path of movement of said carriage stop, signal mechanism, and means for moving said support effectively to sound said signal mechanism when said carriage stop passes a given point in its movement toward said first-named stop, substantially as specified.

14. In a recording machine, line stop mechanism comprising a pivoted member, a spring holding said member in idle position, a support pivoted to said member, a spring holding said support in idle position, a stop carried by said support, and manipulative means for moving said stop from its idle or normal position, substantially as specified.

15. In a recording machine, line stop mechanism comprising a pivoted member, a spring holding said member in idle position, a support pivoted to said member, a spring holding said support in idle position, a stop movably carried by said support, a spring holding said stop in idle position, and manipulative means for moving said stop from its idle position, substantially as specified.

16. Line lock and signal mechanism for a carriage, supported independently of the carriage and comprising a pivoted support, signaling mechanism, means for causing said support to operate said signaling mecha-

nism, a carriage stop pivoted on said support, means holding said support and stop in normal position, and manipulative means for moving said support and stop from their 5 normal positions, substantially as specified.

In testimony whereof, I hereunto affix my signature to this specification this eleventh

day of January 1909, in the presence of two witnesses.

JOSEPH RABER. [L.S.]
